US00D828631S

(12) **United States Design Patent** (10) **Patent No.:** **US D828,631 S**
(45) **Date of Patent:** **** Sep. 11, 2018**

(54) **BICYCLE HELMET**

(71) Applicant: **memBrain Safety Solutions, LLC**, Los Angeles, CA (US)

(72) Inventor: **Isis Alexandra Shiffer**, Brooklyn, NY (US)

(73) Assignee: **memBrain Safety Solutions, LLC**, Los Angeles, CA (US)

(**) Term: **15 Years**

(21) Appl. No.: **29/612,613**

(22) Filed: **Aug. 2, 2017**

Related U.S. Application Data

(63) Continuation of application No. 29/593,908, filed on Feb. 14, 2017, which is a continuation-in-part of application No. 29/582,807, filed on Oct. 31, 2016, now Pat. No. Des. 806,317.

(57) **CLAIM**

The ornamental design for a bicycle helmet, as shown and described.

DESCRIPTION

FIG. 1 is a top perspective view of a bicycle helmet showing my new design;

FIG. 2 is a bottom perspective view of the bicycle helmet of FIG. 1.

FIG. 3 is a front view of the bicycle helmet of FIG. 1.

FIG. 4 is a right side view of the bicycle helmet of FIG. 1.

FIG. 5 is a rear view of the bicycle helmet of FIG. 1.

FIG. 6 is a left side view of the bicycle helmet of FIG. 1.

(Continued)

FIG. 7 is a top view of the bicycle helmet of FIG. 1; and, FIG. 8 is a bottom view of the bicycle helmet of FIG. 1. The dash-dot-dash lines (which represent boundary lines) and the even dash lines form no part of the claimed design.

1 Claim, 8 Drawing Sheets
